IMPULSE GENERATOR

Richard C. Coupland, United States Army,
Norfolk, Va.

Application October 2, 1934, Serial No. 746,533

6 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to an impulse generator employed in a synchronized control system such as is used to control the firing of machine guns between the blades of a rotating propeller of aircraft.

10 The purpose of this invention is to provide a compact impulse generator in which the field member of an electrical unit is employed to releasably hold an impulse transmitting member immovable.

15 A further object is to provide a mechanical arrangement for moving the field member out of engagement with the impulse transmitting member. With the foregoing and other objects in view, 20 the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

25 Fig. 1 is a view in side elevation of a gun control assembly.

Fig. 2 is a longitudinal sectional view of the impulse generator showing the field casing in engagement with the cam follower.

30 Fig. 3 is a similar view with a field casing disengaged from the cam follower.

Fig. 4 is a plan view of Fig. 2 with part of the top broken away.

35 Referring to Fig. 1 the gun control assembly consists of an impulse generator A connected to a trigger motor B by means of an impulse cable and cable housing C.

The impulse generator unit is arranged to constitute a compact integral part of the airplane engine synchronized thereto during or after assembly and it consists of a housing 5 in which is mounted a driven shaft 6 having a gear 7 by which it receives its energy from a driving shaft 8 of the engine. The shaft 6 is supported by anti-friction bearings 9—9 and carries a cam 10 positioned in the lower portion of the housing 5. The shaft 6 rotates at a speed to give a cam impulse for each blade of the propeller of the airplane engine. When the shaft 6 is driven at the same speed as the propeller the cam will have the same

number of lobes as there are blades on the propeller while the number of lobes will be doubled if the shaft is driven at half of the propeller speed.

5 A cam follower 11 arranged parallel to the driven or cam shaft 6 is slidably mounted in the housing 5 and has a foot 12 at its lower extremity which carries a roller 13 adapted to engage the lobes of the cam 10. Threaded in the other end of the follower is a plug 14 in which is secured 10 the impulse cable 15 leading to the trigger motor B. The cable is sheathed in a tube 16 which is secured in a socket 17 removably held in place by a nut 18 threaded to the housing 5.

An electrical control unit within the housing 13 5 comprises an armature 19 and commutator 20 carried by the driven shaft 6 and a magnetic field 21 carried by a casing 22 mounted on anti-friction bearings 23—23 and carrying one of the bearings 9 of the shaft 6. The field 21 is of the 20 permanent magnetic type or as shown of the self-excited type under excitation at all times so that the time lag required to build up a current flow in the closed circuit will be a minimum.

The casing 22 carries brushes 24—24 wiping 25 the commutator 20, and conductors 25—25 lead from the brushes through posts 26—26 to a switch 27 on the control stick 28 of the airplane. When the switch is closed it causes an increase in the current flow and a consequent increase in 30 the magnetic pull between the armature and the field. This increase is sufficient to rotate the casing 22 against the action of a coil spring 29 whose ends are respectively attached to the casing 22 and to the housing 5. The rotational 35 placement of the casing is limited by cooperating stops 30—30^a on the casing and housing.

The lower portion of the casing 22 is formed with a reduced neck 31 to avoid interference with an arm 32 projecting from the cam follower below the shoulder 33 of the casing. A cam 34 on the shoulder 33 of the casing constitutes a sear engageable with a roller 35 on the arm 32 and operating to hold the cam follower immovable. When the casing 22 is rotated as by closing the 40 switch of the electrical circuit, the cam sear 34 is angularly displaced out of the path of movement of the arm 32 and the cam follower is free to reciprocate. When the switch is open the casing 22 is counter-rotated by the spring 29 to 45 place the cam sear in engagement with the arm and again hold the cam follower immovable.

The upper end of the casing 22 carries an axially disposed shaft 36 on which is fixed a pinion 37. A slide 38 mounted in the upper part of the hous- 50 55

- ing 5 includes a rack 39 meshing with the pinion. A cable 40 attached to the slide is actuated by a hand lever 41 placed on the control stick 28 of the airplane. This arrangement provides a mechanical operating mechanism for retracting the slide and causing the casing 22 to be rotated to disengage the cam sear 34 from the arm of the cam follower. The spring 29 restores the parts when pressure on the hand lever 41 is relieved.
- 10 An additional spring 42 may be provided to supplement the action of the spring 29 and is preferably confined between the slide 38 and a socket member 43 which is threadedly secured to the housing 5.
- 15 15 The trigger motor unit B, which forms the subject of a separate application, includes a spring 44 which is generally common to this type of mechanism as seen in my prior Patent 1,770,125 of July 8, 1930. This spring acts on a slide 45 which receives the impulse transmitted by the cable 15 and the spring serves to restore the slide when the cam follower is not acted on by the cam 10. When the cam follower is depressed by the cam 10 the cable 15 retracts the slide 45 and compresses the spring 43.
- 20 25 I claim:
1. In a synchronized mechanism, an impulse generator including a housing, a driven cam shaft in the housing, a cam follower in the housing, an armature on the cam shaft, a casing rotatable about the axis of the cam shaft, a magnetic field on the casing, an electrical circuit between the armature and casing and including a switch, a spring for counter-rotating the casing, a cam 30 on the casing engageable with the cam follower to hold it immovable, a pinion on the casing, a rack slidably mounted in the casing and meshing with the pinion, and means for retracting the rack.
  - 35 40 2. In a synchronizing mechanism, an impulse generator including a housing, a driven cam shaft in the housing, a cam follower in the housing, an armature on the cam shaft, a casing rotatable about the axis of the cam shaft, a magnetic field

on the casing, an electrical circuit between the armature and casing and including a switch, a spring for counter-rotating the casing, a cam on the casing engageable with the cam follower to hold it immovable, and means for mechanically rotating the casing out of engagement with the cam follower.

5

3. In a synchronizing mechanism, an impulse generator including a housing, a driven cam shaft extending into the housing, a cam follower in the housing, an electrical unit within the housing including an armature driven by the cam shaft and a rotatable field member, a spring for the field member, means on the field member engageable with the cam follower to hold it immovable 10 and means for mechanically rotating the field member.

15

4. In a synchronizing mechanism, an impulse generator including a housing, a driven cam shaft extending into the housing, a cam follower in the housing, an electrical unit within the housing including an armature driven by the cam shaft and a rotatable field member, a spring for the field member, means on the field member engageable with the cam follower to hold it immovable 20 and means for mechanically rotating the field member.

25

5. In a synchronizing mechanism, the combination with a driven cam shaft and a cam follower, of an electrical unit including a rotatably mounted field member releasably engaging the cam follower to hold it immovable, a spring normally holding the field member in position to engage the cam follower, a pinion on the field member and a rack meshing with the pinion.

30

6. In a synchronizing mechanism, the combination with a driven cam shaft and a cam follower, of an electrical unit including a rotatably mounted field member releasably engaging the cam follower to hold it immovable, a spring normally holding the field member in position to engage the cam follower, and means for mechanically rotating the field member out of engagement with the cam follower.
